UNITED STATES PATENT OFFICE.

GEORGE LEMAIN, OF PAWTUCKET, RHODE ISLAND.

COTTON-GIN RIB.

SPECIFICATION forming part of Letters Patent No. 510,073, dated December 5, 1893.

Application filed August 28, 1893. Serial No. 484,215. (No model.)

To all whom it may concern:

Be it known that I, GEORGE LEMAIN, a citizen of the United States, residing at Pawtucket, in the county of Providence and State 5 of Rhode Island, have invented certain new and useful Improvements in Cotton-Gin Ribs, of which the following is a specification, reference being had therein to the accompanying drawings, in which—

10 Figure 1 is a perspective view of a gin-rib provided with my improvement, and Fig. 2 is a longitudinal sectional view of that part of the rib provided with my device.

The object of this invention is to provide 15 each rib in a saw-gin with a removable wearing plate, which can be readily removed and renewed, when worn, without the use of tools, and which shall form practically a part of the rib when in place and which shall not 20 add materially to the cost of the rib, as more fully hereinafter appears.

In the drawings *a* designates the rib, which is of the usual construction, excepting that it is provided across its face, at the point 25 where the saw-teeth pass between the ribs, with a transverse recess in which is fitted the wearing-plate *b*, this plate being set in flush with the surface and side edges of the rib. The upper and lower edges of plate *b* are beveled 30 downwardly and inwardly and fit closely against the correspondingly beveled walls of the recess, and the lower edge has formed on it a downwardly-extending lug *b'*, which has its lower edge beveled and fits in a correspondingly beveled recess in the rib. A sliding-bolt *c* works in a longitudinal recess in the upper edge of the wearing-plate and is 35 adapted to automatically spring upward into a bolt-hole formed in the adjacent beveled edge of the rib-recess, the actuating-spring being confined in the recess behind the bolt and the bolt and spring being guided by a pin *c'* formed on the rear end of the bolt and working in a smaller recess *c''* behind the 40 main bolt-recess. A pin *d* is secured in the bolt and extended out through a slot *d'* in the wearing plate and provided with an operating-knob *d''* which works on the surface of the wearing-plate and is sufficiently long to 45 cover the slot and extend across the joint between the plate and rib and has its surface beveled downwardly and inwardly to a thin edge. It will be observed that the wearing 50

plate may be readily removed by simply pressing down the knob *d''* to disengage the bolt, 55 and then swinging the upper edge of the plate outwardly. The beveled lower edge of the plate prevents it swinging outwardly and the lug prevents lateral or edgewise displacement, while the bolt performs the same function for the upper edge of the plate. The operating knob is so beveled that the fiber 60 will not become entangled with it; in fact, the manner of beveling the knob causes the pressure of the cotton to assist in holding the 65 bolt locked. This wearing plate is very simple and is therefore easily and cheaply constructed, and it is also easily removed and replaced by a new one when worn, thereby avoiding the necessity and expense of putting new ribs in a machine when they become worn.

The device forms practically a part of the rib when in place and is not liable to become loosened from use and does not require 75 the use of tools for removal and replacement.

Having thus fully described my invention, what I claim is—

1. In combination, a gin-rib provided with a transverse recess in its face, a plate fitting 8c in said recess and carrying a spring-actuated bolt at one end, said bolt being adapted to enter a recess in the rib and lock the plate in place, substantially as described.

2. In combination, a gin-rib provided with 85 a transverse recess in its face, a plate fitting in said recess and carrying a spring-actuated bolt at one end, said bolt being adapted to enter a recess in the rib and lock the plate in place, and an operating-knob connected to 90 said bolt, this knob working on the front of the plate and having its face beveled, substantially as described.

3. A gin-rib provided with a recess across 95 its face, a wearing-plate fitting therein and provided with a lug at one end, entering a recess in the rib, and a spring-actuated bolt at its other end, and means for operating the bolt, substantially as described.

In testimony whereof I affix my signature in 100 presence of two witnesses.

GEORGE LEMAIN.
